UNITED STATES PATENT OFFICE.

DOUGLASS BERRY KERSHAW, OF LYNCHBURG, VIRGINIA, ASSIGNOR TO PATRICK HENRY CASEY, OF LYNCHBURG, VIRGINIA.

FILM FIRE-SCREEN.

,022,320.

Specification of Letters Patent.

Patented Apr. 2, 1912.

Application filed March 25, 1911. Serial No. 616,810.

To all whom it may concern:

Be it known that I, DOUGLASS BERRY KERSHAW, a citizen of the United States, and a resident of Lynchburg, in the county of 5 Campbell, State of Virginia, have invented a new and useful Improvement in Film Fire-Screens, of which the following is a specification.

My invention is an improvement in film 10 fire screens, and consists in certain novel constructions and combinations of parts herein-after described and claimed.

The object of the invention is to provide 15 a screen for protecting the films in kinematograph apparatus from fire in case of breakage of the film while the apparatus is in use.

Referring to the drawing forming a part 20 hereof: Figure 1 is a side view of a part of an apparatus of the character specified provided with the improvement, Fig. 2 is a rear view of the same, and Fig. 3 is an enlarged detail view of the governor.

In the drawing the kinetoscope frame 1 is 25 provided with an opening 2 through which the pictures on the film 3 are projected by means of the usual lighting device (not shown) arranged on the opposite side of the film from the opening. The film is supported by a pair of rollers 4 and 5 above the opening, and by a sprocket reel 6 below the opening. A plate 7, having an opening 8 registering with the opening 2, is supported on the kinetoscope frame, by means of legs 9 on the plate which rest against brackets 10 30 on the frame. The shaft 11 of the roller 4 is supported in bearings 12 on the plate 7, and is provided with a gear wheel 13 outside of the bearings. The reel 6 is secured to a shaft 14, journaled in bearings 15, and 40 at one end the said shaft is provided with a gear wheel 16. The opposite end of the shaft 14 is provided with a pulley 17.

The screen 18 is of approximately pear or fan shape and is pivoted at its small end on 45 a journal pin 19 on the door frame 20, which closes against the rear face of the film and holds it flat against the plate 7, so that the plane of the picture on the film at this point is exactly parallel with the projecting screen. 50 The screen is provided with a bearing 21 for receiving the pin 19, and is held in place on the pin 19 by a cotter pin 22. An arm 23 extends downwardly and outwardly from the small end of the screen, the arm being arranged at an angle with respect to the long

axis of the screen. A counterbalance in the form of a weight 24 is slidable on the arm and is held in adjusted position by a set screw 25.

A governor is mounted on a shaft 26 journaled in a bearing bracket 26^a at one side and perpendicular to the plane of the screen. The governor comprises a sleeve 27 secured to the shaft by a pin 28, and a sleeve 29 slideable on the shaft, and connected to the fixed sleeve by spring plates 30, each of which has a ball weight 31 secured to its center. A disk 32 is secured to the sleeve 29 at its rear end and the disk is concentric with the sleeve.

The shaft 26 is provided with a beveled pinion 39, meshing with a bevel wheel 40 on the shaft 41, journaled in bearings 42 on the frame, and the said shaft is provided with a sprocket or toothed reel 43 for engaging the film. It will be understood that the teeth or sprocket points of the reels 6 and 43 engage the usual perforations 44 in the side edges of the film.

With the above described construction, the film operates the governor, after the said film 80 has passed over the projecting opening.

One face of the disk 32, before mentioned, is engaged by a roller or wheel 44^a journaled on one of the arms 45 of a rock shaft 46, having another arm 47 connected by a link 48, 85 with a lateral lug 49 on the screen 18. The rock shaft is supported by pointed set screws 50, threaded through the arms 51 of a yoke shaped bracket 52 on the frame, the pointed inner ends of the screws engaging recesses 90 in the ends of the shaft. The mounting of the rock shaft is thus very delicate so that it will answer readily to changes in the governor. It will be evident that when the ball weights 31 constrain the sleeve 29 to move 95 toward the sleeve 27, the disk will also be moved, and the rock shaft will be oscillated, in a direction to release the pull on the screen 18, so that the counterbalance 23 may move 100 the said screen away from over the projecting opening.

In operation the film is driven by the usual means engaging the wheels 13 and 16. The film is held against the plate 7 by means of rollers, one of which 3^a is indicated by dotted lines in Fig. 1. The counterbalance 23 acts normally to move the screen away from over the opening, but the action of the said counterbalance is counteracted by the pull of the rock shaft on the link, and 110

the said pull is maintained by the spring arms 30 upon which the ball weights are mounted. As long as the film moves, the governor will be operated, and the disk 5 32 will be moved to release the pressure on the rock shaft 46, so that the counterbalance may move the screen into inoperative position. Should however, for any reason, the film cease to move, as for instance, through 10 breakage of the film, the pull on the link 48 will be released, and the screen will be permitted to swing into active position over the film, thus protecting it from undue heat, and danger of fire.

15 As is well known, the films used in apparatus of the character in question are very inflammable, and since the illuminating device must be of high power, the film will almost certainly be ignited should the rays 20 of light act upon any portion thereof for any great length of time. With the improvement in place any accident to the kinetoscope that will stop the film will cause the mechanism to interpose the screen between 25 the film and the light to shield the film from the direct rays, so that it cannot become overheated. It will be evident that the governor acts normally to move the screen out of protective position.

30 I claim:—

1. In combination with a kinetoscope and the film moved thereby, of a screen pivoted adjacent to the film and between the film and the source of light and mounted to 35 swing over and away from over the film, an arm extending from the screen on the opposite side from its pivotal mounting, a weight slidable on the arm, means for holding the weight in adjusted position, a rock 40 shaft having radial arms arranged at an angle to each other journaled adjacent to the screen, a link connecting one of the arms to the screen on the opposite side of the pivotal mounting from the weighted arm, a 45 roller over which the film passes and rotated by the passage of the film, a governor shaft, a driving connection between the said shaft and the roller, a governor on the shaft, said governor comprising a collar fixed to the 50 shaft, and a sleeve movable longitudinally of the shaft, spring plates connecting the sleeve and the collar, a weight connected with the center of each plate, and a disk connected with the sleeve and bearing 55 against the other arm of the rock shaft, the governor when in normal position holding the screen over the film.

2. In combination with a kinetoscope and the film moved thereby, of a screen pivoted 60 adjacent to the film and between the film and the source of light and mounted to swing over and away from over the film, a rock shaft having radial arms journaled adjacent to the screen, a link connecting 65 one arm of the shaft to the screen, a roller

over which the film passes and rotated by the said film, a governor shaft, a driving connection between the said shaft and the roller, a governor on the shaft, said governor comprising a collar fixed to the shaft, 70 and a sleeve movable longitudinally thereof, spring plates connecting the sleeve and the collar, a weight connected with the center of each plate, a disk connected with the sleeve and bearing against the other arm 75 of the rock shaft and normally holding the screen over the film, and means on the other side of the screen from its pivotal connection for moving the same away from over the film when the governor is in operation. 80

3. In combination with a kinetoscope and the film moved thereby, of a screen pivoted adjacent to the film and between the film and the source of light and mounted to swing over and away from over the film, 85 a rock shaft journaled adjacent to the screen, a link connecting one arm of the shaft to the screen, a roller over which the film passes and rotated by the said film, a governor shaft, a driving connection between the said shaft and the roller, a governor on the shaft, said governor comprising a collar fixed to the shaft, a sleeve movable longitudinally thereof, spring plates connecting the sleeve and the collar, a 90 weight connected with each plate, and a disk connected with the sleeve and bearing against the other arm of the rock shaft and normally holding the screen over the film when the governor is inoperative. 95

4. In combination with a kinetoscope and the film moved thereby, of a screen pivoted adjacent to the film and between the film and the source of light and mounted to swing over and away from over the film, a 100 rock shaft journaled adjacent to the screen, a link connecting one arm of the shaft to the screen, a roller over which the film passes and rotated by the said film, a governor shaft, a driving connection between the said shaft and the roller, a governor on the shaft, a disk slidable on the shaft and operated by the governor, said disk bearing against the other arm of the rock shaft, and normally holding the screen over the 110 film when the governor is inoperative, and a weight connected with the screen and adjustable toward and from the same for moving the screen away from the film. 115

5. In combination with a kinetoscope and the film operated thereby, of a screen mounted adjacent to the film for swinging movement over and away from over the film between said film and the source of light, a 120 rock shaft journaled adjacent to the screen, a connection between one arm of the shaft and the screen, a roller over which the film passes and rotated by the film, a governor shaft, a driving connection between the 125 shaft and the roller, a governor on the shaft, 130

- a disk slidable on the shaft and bearing against the other arm of the rock shaft and normally holding the screen over the film when the governor is inoperative, and a 5 counterbalance acting normally to swing the screen away from over the film.
6. In combination with a kinetoscope and the film operated thereby, of a screen mounted adjacent to the film for swinging movement over and away from over the film between said film and the source of light, a rock shaft journaled adjacent to the screen, a connection between one arm of the shaft and the screen, a roller over which the film 10 passes and rotated by the film, a governor shaft, a driving connection between the shaft and the roller, a governor on the shaft, and a connection between the governor and the other arm of the rock shaft for operating the said shaft, and normally holding the screen over the film when the governor is inoperative, and a counterbalance acting normally to swing the screen away from over the film.
- 15 7. In combination with a kinetoscope and the film operated thereby, of a screen mounted adjacent to the film for swinging movement over and away from over the film between said film and the source of light, a rock shaft journaled adjacent to the screen, a connection between one arm of the shaft and the screen, a roller over which the film passes and rotated by the film, a governor 20 driven by the roller, a connection between the governor and the other arm of the rock shaft for operating the said shaft, and normally holding the screen over the film when the governor is inoperative, and a counterbalance acting normally to swing the screen away from over the film.
- 25 8. In combination with a kinetoscope and the film operated thereby, of a screen mounted adjacent to the film for swinging movement over and away from over the film between said film and the source of light, a rock shaft journaled adjacent to the screen, a connection between one arm of the shaft and the screen, a roller over which the film 30 passes and rotated by the film, a governor driven by the roller, a connection between the governor and the other arm of the rock shaft for operating the said shaft, and normally holding the screen over the film when the governor is inoperative, and a counterbalance acting normally to swing the screen away from over the film.
- 35 9. In combination with a kinetoscope and the film operated thereby, of a screen mounted adjacent to the film for swinging movement over and away from over the film between said film and the source of light, a counterbalance acting normally to swing the screen away from over the film, a roller 40 driven by the passage of the film, a governor driven by the roller, and means operated by the governor when in inoperative position for holding the screen over the film.
- 45 10. In combination with a kinetoscope and the film operated thereby, of a screen mounted adjacent to the film for swinging movement over and away from over the film between the film and the source of light, a counterbalance acting normally to swing the screen away from over the film, a roller driven by the passage of the film, a governor 45 driven by the roller, and means operated by the governor when in inoperative position for holding the screen over the film.
11. In combination with a kinetoscope and the film operated thereby, of a screen mounted adjacent to the film for swinging movement over and away from over the film, means acting normally to swing the screen away from over the film, a roller driven by the passage of the film, means for 50 moving the screen over the film, and means operated by the movement of the roller for restraining the action of the said means.
